PISTON RING

Filed Nov. 1, 1951

2 Sheets-Sheet 2

Fig. 3.

Fig. 4.

The diagram illustrates a block structure composed of five rectangular units. Each unit has a height of 15, a width of 10, and a depth of 23. The front-most unit is labeled with a height of 24 and a depth of 17. The second unit from the front is labeled with a height of 24 and a depth of 16. The third unit is labeled with a height of 24 and a depth of 18. The fourth unit is labeled with a height of 24 and a depth of 17. The fifth unit is labeled with a height of 24 and a depth of 16. The total width of the structure is 50 (10 units of 5 units each). The total depth is 82 (23 units of 5 units each). The total height is 75 (15 units of 5 units each).

PISTON RING

Hsia-Si Pien, Drexel Hill, Pa., assignor to Wilkening Manufacturing Company, Philadelphia, Pa., a corporation of Delaware

Application November 1, 1951, Serial No. 254,345

5 Claims. (Cl. 309—29)

1

The present invention relates to a 3-piece piston-ring for internal combustion engines and the like and relates more particularly to a spring-expanded multi-seal compression ring.

For the purpose of illustrating the invention, there is shown in the accompanying drawings one form thereof which is at present preferred, although it is to be understood that the various instrumentalities of which the invention consists can be variously arranged and organized and that the invention is not limited to the precise arrangement and organization of the instrumentalities as herein shown and described.

In the accompanying drawings in which like reference characters indicate like parts:

Figure 1 represents an elevational view of the piston-ring embodying the present invention, partly in section, shown disposed in the ring-receiving groove of a piston.

Figure 2 represents an "exploded" perspective view of the piston-ring embodying the present invention.

Figure 3 represents a fragmentary plan view of a strip or band of spring-metal from which the spacer and expander is formed, shown in its first stage of development.

Figure 4 represents a section on line 4—4 of Figure 3.

Figure 5 represents a fragmentary plan view of the spacer and expander strip in the second stage of its development.

Figure 6 represents a section on line 6—6 of Figure 5.

Figure 7 represents a fragmentary perspective view of the completed spacer and expander strip after it has been curved or bent into a generally circular formation.

Figure 8 represents an enlarged cross-sectional view of the piston-ring of the present invention disposed in a ring-receiving groove of a piston.

The 3-piece compression ring of the present invention is formed of a pair of relatively thin flat cylinder-contacting ring elements or seals 11 and 12 respectively and an intervening spacer and expander 13 of generally T-shaped cross-section with the bottom edge 14 of the T being spaced inwardly slightly from the outer peripheral edges 19 of the seals 11 and 12 and with the two arms 17 and 18 of the T being disposed within the inner peripheral edges 33 and 34 of the seals 11 and 12 and forming seal-engaging and seal-expanding lugs or ears.

The spacer and expander 13 is formed of a flat strip or band of spring metal of suitable thickness as indicated in Figures 3 and 4, and may

be spring-steel. The more or less-continuous flat band or ribbon of spring steel or other spring metal is then notched or slotted alternately from opposite edges as by the slots 23 and 24; this being preferably done on a punch press. The slots 23 and 24 are so staggered in relation to each other and are of such length as to leave a more or less corrugated formation as indicated in Figure 3. The slots or notches 24 are deeper than the slots or notches 23. This leaves a successive series of outer circumferentially disposed portions 15 and inner circumferentially disposed portions 16, overlapping each other and connected by means of the transverse legs 10. The inner circumferential portions 16 are then bent alternately in opposite directions to form the lugs 17 and 18. The so formed strip is then curled into circular form as indicated in Figures 2 and 7. This can be done by coiling it to suitable diameters and then cutting the individual convolutions to form individual spacers and expanders.

The thickness of the metal of which the spacer and expander is formed is such that combined with the thicknesses of the two sealing rings 11 and 12, in the assembled and operative condition indicated in Figures 1 and 8, the composite 3-piece ring will neatly fit within the width of the ring-receiving groove 26, with requisite clearance.

The sealing rings 11 and 12 are generally continuous except for a gap, and may be so set that the gap will be slightly open or substantially closed in the free or relaxed condition of the sealing members 11 and 12; bearing or contacting of these sealing elements 11 and 12 against cylinder wall 22 being dependent primarily upon the outward radial expanding force exerted by the spacer and expander 13 against the inner peripheries 33 and 34 of the seals 11 and 12.

The spacer and expander 13 is likewise formed with a gap 25, with the free ends 27 and 28 thereof abutting each other when the spacer and expander is mounted and operatively compressed within the ring-receiving groove 26 of the piston.

The circumferential length of the expander 13 is such that when the rings 11 and 12 are mounted thereon in the manner indicated in Figures 1 and 8, with the rings 11 and 12 in contact with the cylinder-wall 22, the successive corrugations of the expander will be resiliently deformed or compressed slightly or crowded slightly within the confines of the inner peripheries of the rings 11 and 12. The expander 13 then, acting through lugs 17 and 18 thereof, exerts uniformly dis-

tributed outward radial expanding force against the rings 11 and 12. This outward radial expanding force may be varied by varying the overall circumferential length of the expander as well as by the thickness of the metal thereof and the depth and width of the slots 23 and 24, so as to vary the unit of pressure per unit of contact area between the rings 11 and 12 on the one hand and the cylinder-wall 22 on the other hand, to the amount most effective for the desired sealing of the piston to the cylinder-wall against the passage of compressed gases under pressure from the combustion chamber or compression chamber.

The expander 13 is preferably made of spring steel tempered to suitable spring temper, but other resilient spring metal may be used.

The sealing rings or "rails" 11 and 12 are also preferably made of steel of suitable hardness. However, the sealing rings or "rails" 11 and 12 may also be formed of suitable cast iron. The outer cylinder-contacting peripheral surfaces 19 of the rings 11 and 12 may be chromium plated.

The overall radial width of the composite compression ring is such that the expander 13 will not contact or "bottom" against the inner wall of the ring-receiving groove when the piston ring is operatively mounted therewithin.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, the following is hereby claimed:

1. A multi-piece spring-expanded piston-ring comprising a plurality of spaced-apart sealing rings, and a generally flat and generally annular intervening corrugated spacer and expander spring intermediate said sealing rings and spacing them apart, having one complete gap therein to form two separate abuttable ends and having its corrugations extending to-and-fro in a generally radial direction and being circumferentially compressible with its free ends in abutting relation to each other, and having seal-engaging lugs at its inner periphery extending axially therefrom into engagement, alternately, with the inner peripheries of the opposed sealing-rings.

2. A multi-piece piston-ring comprising a pair of generally flat split annular sealing rings of uniform cross-section spaced apart from each other, a generally flat and split generally annular corrugated and circumferentially compressible spacer and expander spring intermediate said sealing rings formed of a flat sheet of spring metal notched inwardly from its opposite edges to form the corrugations and having seal-engaging lugs bent alternately in opposite directions generally at a right angle to the plane of the sheet along the inner periphery of said

spacer and expander, said lugs being disposed in operative relation to and operatively engaging the inner peripheries of said sealing rings to expand them outwardly; the corrugated sheet spacing the sealing rings in relation to each other and in relation to the ring-receiving groove.

3. A 3-piece piston-ring comprising a generally annular and circumferentially resilient and compressible non-bottoming seal-supporting expander having one gap therein interrupting the generally annular continuity thereof and forming two separate abuttable ends and having a pair of spaced and opposed sets of seal-supporting and spacing lands in spaced parallel planes generally at a right angle to the axis of piston-ring and having inner seal-backing projections extending axially outwardly therefrom alternately in opposite directions substantially beyond the plane of said seal-supporting lands and adapted to engage the respective inner peripheries of a corresponding pair of cylinder-contacting seals, and a pair of flat and generally continuous split annular uniform-cross-sectioned seals disposed on opposite sides of said seal-supporting expander along said seal-lands thereof with the inner peripheries of said seals in operative juxtaposition to said projections so as to be engaged thereby and to be expanded radially outwardly when said 3-piece piston-ring is confined within cylinder-diameter with the ends of said seal-supporting expander in abutting relation to each other and with the inner peripheries of the seals in operative engagement with said projections.

4. A generally annular spacer and expander for multi-piece piston-rings comprising a generally corrugated and circumferentially compressible body with the corrugations extending to-and-fro generally in a radial direction, the inner ends of the successive corrugations being formed with ring-engaging and ring-expanding lugs extending alternately in opposite and generally axial directions substantially beyond the sides of said body.

5. A generally annular and circumferentially compressible resilient spacer and expander for multi-piece rings comprising a generally flat corrugated sheet of spring metal with the corrugations formed therein by spaced notches extending into it alternately from opposite edges in a generally radial direction, and ring-engaging and ring-expanding lugs bent in a generally axial direction from the inner ends of said corrugations, alternately in opposite directions and substantially beyond the sides of said spacer and expander.
